UNITED STATES PATENT OFFICE

161,230

COMBINED PLANT RECEPTACLE AND SUPPORT

Bernard Yellin, Chicago, Ill.

Application January 12, 1950, Serial No. 7,174

Term of patent 7 years

(Cl. D35—3)

To all whom it may concern:

Be it known that I, Bernard Yellin, a citizen of the United States and resident of Chicago, in the county of Cook and State of Illinois, have invented a new, original, and ornamental Design for a Combined Plant Receptacle and Support, of which the following is a specification, reference being had to the accompanying drawing, forming a part thereof.

Fig. 1 is a front perspective view of a combined plant receptacle and support, showing my new design.

Fig. 2 is a side elevational view of the same.

Fig. 3 is a sectional view of the same taken along the line 3—3 of Fig. 1 and in the direction indicated by the arrow.

I claim:

The ornamental design for a combined plant receptacle and support, substantially as shown.

BERNARD YELLIN.
